UNITED STATES PATENT OFFICE.

FRED DE CARDY, OF CHICAGO, ILLINOIS, ASSIGNOR TO WHITE BRASS CASTINGS COMPANY, OF CHICAGO, ILLINOIS, A CORPORATION OF ILLINOIS.

MOTOR-METER LOCK.

Application filed August 27, 1923. Serial No. 659,467.

To all whom it may concern:

Be it known that I, FRED DE CARDY, a citizen of the United States, and a resident of Chicago, in the county of Cook and 5 State of Illinois, have invented certain new and useful Improvements in a Motor-Meter Lock, of which the following is a full, clear, and exact description, such as will enable others skilled in the art to make and use 10 the same.

My present invention relates to improvements in radiator caps for automobiles and particularly to radiator caps of a decorative design and in which may be installed a 15 motormeter or other device for indicating the temperature of the water in the radiator. A highly desirable, if not necessary, feature of such devices is that they should be so constructed that when attached to the 20 radiator it will be very difficult or impossible to remove them and thereby prevent the theft of the cap and the motormeter or other temperature indicating device mounted thereon. It has therefore been 25 one of the objects of my present invention to provide a radiator cap which may be readily installed, but which, after installation, will be extremely difficult or impossible of removal. Other objects of my invention 30 are to provide a neat and attractive radiator cap which can be manufactured and sold at an economical figure.

I prefer to attain the foregoing objects by means of the structure illustrated in the 35 accompanying drawing, in which,

Figure 1 is a front or forward elevation of a radiator cap embodying my invention; and mounted upon a radiator spout.

Figure 2 is a central transverse section of 40 the structure shown in Fig. 1 with a fragment of the upper frame of a motormeter assembled therewith;

Figure 3 is an elevation of the inner element of the cap;

Figure 4 is an elevation of the intermediate element of the cap which makes 45 screw-threaded assembly with the spout of a radiator;

Figure 5 is a top plan of the structure 50 shown in Fig. 4;

Figure 6 is a section of a modified form of the structure shown in Fig. 4 for assembly with an exteriorly threaded radiator spout; and

Figure 7 is a plan of the split ring for

retaining the motormeter connection cover in place.

Figure 8 is a fragmental plan.

The cap comprises an exterior preferably cylindrical casing, 8, provided upon one side 60 with parallel upwardly extending ears or brackets, 9, between which is pivoted a plate, 10, extending from a closure or cover, 11. This closure or cover is provided with a forwardly extending embossment, 12, over 65 which engages a wire loop or bale, 13, the ends of which are pivoted in oppositely bored embossments, 14, provided upon the forward portion of the casing, 8.

For decorative purposes I have provided 70 ball headed arms, 15, extending from each side of the casing, 8.

The casing, 8, is of a size to rest upon the top of the radiator spout, X, with which it is to be assembled, and the lower portion 75 of the bore of the casing, 8, is reduced to provide a shoulder, 16. The casing, 8, is secured to the radiator spout by means of the intermediate element, 17, which is an annulus, the lower end of which is exteriorly threaded to screw into the end of the radiator spout, and from the upper edge of which extends a rib or flange, 18, to engage the shoulder 16 of the casing, 8.

The structure, as so far described, will 80 permit the turning of the outer casing without turning the intermediate element or annulus, 17, and thereby detaching the cap from the radiator spout, but if a pair of pliers which will engage both the casing and annulus are employed these members may be detached from the radiator. To prevent such a contingency I have set into the top face of the annulus a spring ratchet dog 85 or detent, 19, and have provided an additional annulus, 20, having a lateral flange, 21, at its upper edge which extends over and covers the top of the intermediate element, 17, and which is long enough to extend to the bottom of said intermediate element and prevent access thereto. The under edge of the flange 21 is cut back to provide 90 a shoulder, 22, for engaging the dog or detent 19, and a screw 8 is inserted through the casing 8 to lock the annulus 20 thereto 95 temporarily. When the structure is placed on the radiator spout X the arms 15 are rotated causing a rotation of casing 8 and the interior annulus 20 which is temporarily 100 locked thereto, and shoulder 22 of said an-

105

110

nulus engages with the dog or detent 19 on the intermediate annulus 17 so that the latter is rotated with the structure and is screwed into the spout of the radiator. A 5 rotation of the structure in the opposite direction will not disturb the annulus 17 because the shoulder 22 will be disengaged from the dog or detent, and said annulus cannot be unscrewed from the spout, and 10 consequently the cap cannot be removed. Upon completing the mounting or assembling operation the screw S may be removed and the arms 15 and casing 8 may be rotated in either direction.

15 In Fig. 6 I have shown the intermediate annulus, 17, interiorly, instead of exteriorly, threaded, but, it is obvious this makes no difference in the manner of operation of my device.

20 A packing washer, 23, is preferably placed upon the top of the inner element before the cover is closed. Also it should be noted that the cover is so proportioned that the inner element must be inserted in 25 the casing 8 before the cover is assembled and cannot be taken out until the cover is disassembled from the casing. As the cover pintle does not extend entirely through one of the ears 9 this is a difficult job requiring 30 the requisite tools, skill and time, and is not a job which would be attempted by an unauthorized person upon the street or in a public place.

In connection with the motormeter which 35 is installed in the cover I have provided the centrally perforated washer, 24, the edge, 25 of which is slightly dished, and I have

provided the interior of the closure or cover, 11, with a comparatively deep groove, 27, to receive the dished edge of the washer, and 40 a split ring 28 to retain the washer in the groove. The ends of the split ring, 28, are both bevelled backwardly from the outer periphery of the ring so that the ring and disk or washer cannot be easily removed, 45 thereby further discouraging unauthorized tampering with the cap or motormeter.

What I claim is:—

1. A radiator closure comprising an annulus having a lateral shoulder thereon, a 50 centrally perforated cap hingedly secured to said annulus, a threaded union element having a flange engaging with the shoulder of said annulus, an interior element covering the juncture of said before-mentioned annulus and said union element, a pawl and ratchet co-actively relating said union and covering elements, and means for preventing the withdrawal of said covering element.

2. A radiator closure comprising an interiorly shouldered sleeve, a cap hingedly mounted thereon, an exteriorly shouldered tube rotatably mounted in said sleeve and threaded for screw engagement with a radiator spout, a third member upon the interior of said tube, and means interposed between said tube and third member for securing combined movement of said parts in one direction.

Signed at Chicago, county of Cook and 70 State of Illinois, this 12th day of July, 1923.

FRED DE CARDY.
